UNITED STATES PATENT OFFICE.

ABRAHAM T. HARPER, OF PORTLAND, MAINE; JAMES W. HARPER ADMINISTRATOR
OF SAID ABRAHAM T. HARPER, DECEASED.

PAPER-CUTTER.

1,116,886.

Specification of Letters Patent. Patented Nov. 10, 1914.

Application filed June 19, 1913. Serial No. 774,503.

To all whom it may concern:

Be it known that I, ABRAHAM T. HARPER, a citizen of the United States, residing at Portland, in the county of Cumberland and 5 State of Maine, have invented certain new and useful Improvements in Paper-Cutters, of which the following is a specification.

Figure 1 is a plan view of my device; Fig. 2 is a detail elevation of my improved 10 transverse adjustable gage; Fig. 3 is a detail showing pivot and washer; and Fig. 4 is a detail of the blank for the spring which holds the movable blade with yielding tension.

15 Same reference letters indicate like parts in the several figures.

In said drawing A represents a table or base to the side of which is attached a stationary cutting blade B. Outside of and 20 adjacent to said blade B and pivotally attached at one end thereto is a movable cutting blade C. The blade C is attached to the blade B by means of a pivot bar D. Said bar is provided with a threaded nut F 25 on the end thereof, and interposed between nut F and blade C is a pronged spring E and a washer G, the washer G being provided with a dog G' adapted to take into a longitudinal groove D' in the pivot bar 30 and being located between the spring and nut. The pivot is rigidly inserted in the stationary blade and the construction of the washer is such that it can not be turned on the pivot bar. The movable blade and the 35 spring turn on the pivot bar. Thus constructed, there is no tendency of the nut to loosen by repeated action of the movable blade. The movable blade is provided on its pivot end with a slight offset H beyond 40 the pivot point so that, when the spring is set, it holds the free end of the blade with a yielding tension against the stationary blade, so that the movable blade always moves against the stationary blade with a 45 shearing cut, thus preventing any possibility of the two cutting edges failing to coincide at all cutting points. Mounted in the base is an adjustable gage I set on a spindle J passing through the base, said 50 spindle being provided with a stop J' on the inside of the gage and with a removable nut K on the outside thereof, so that the gage I may be detached from its supporting

spindle for convenience in packaging. The gage is parallel with the cutting blades and 55 is adjustable in the base, and may be held in any position by means of a set screw L set in the base and adapted to be turned into engagement with the spindle. In a transverse recess M located in the base near the 60 pivot point is an adjustable gage N provided with angle sockets O, and on its inner end with a projection P substantially equal to the width of the stationary cutter. The upper edge of the gage N is normally above 65 the plane of the top of the table. The gage is held in place by means of pins Q which pass through angle sockets in the gage. In the normal position of the gage the pins are in the horizontal portions O of the angle 70 sockets. When it is desired to cut a piece of paper longer than the table, the gage M may be moved away from the cutting blades, and then falls in the recess until the pins are in the top of the vertical portions O' of 75 the angle sockets, thus leaving the paper free to slide beyond the end of the table and the cut is then completed by another movement of the cutting blades.

Having thus described my invention and 80 its use, I claim:

1. In a paper cutter, a table, a cutting blade rigidly secured to said table, a pivot bar rigidly secured to said cutting blade, a movable cutting blade pivotally mounted 85 upon said pivot bar, a washer rigidly mounted upon said pivot bar, and a pronged spring pivotally mounted upon said pivot bar between said movable blade and said washer. 90

2. In a paper cutter, a table, a stationary blade secured thereto, a movable cutting blade pivotally attached to said stationary blade, a transverse groove in said table near the pivot end of the blades and a gage adjustable vertically and transversely of the 95 table.

3. In a paper cutter, a table, a stationary cutting blade secured thereto, a movable cutting blade pivotally attached to said stationary blade, a gage lying parallel with and outside of the cutting blades and adjustable relative thereto, and an adjusting gage at right angles to said cutting blades and adjustable vertically and transversely 100 relative thereto. 105

4. In a paper cutter, a table, a stationary blade secured thereto, a movable blade pivotally attached to said stationary blade, said table being provided with a groove at right angles to said blades, an adjustable gage set in said groove and provided with angle sockets, and pins extending through said

angle sockets, whereby said gage is adjustable vertically and endwise in said groove.

ABRAHAM T. HARPER.
